LAMP SOCKET FOR PHOTOFOLASH UNITS

Edward S. McKee and Edmund F. Deffenbaugh, Rochester, N. Y., assignors to Eastman Kodak Company, Rochester, N. Y., a corporation of New Jersey

Application May 18, 1956, Serial No. 585,750

2 Claims. (Cl. 339—45)

The present invention relates to photoflash units for cameras and particularly to a dual lamp socket for such photoflash units which is adapted to interchangeably and releasably seat different types of conventional flashlamps, i. e., a lamp having a small diameter base and having a circumferential groove therein (M-2 flashlamp) or a lamp having a larger diameter base and having bayonet pins extending radially therefrom (#5 and #25 flashlamps).

The first small size flashlamps, i. e. #5, #25, SM, etc., had a base provided with two diametrically spaced bayonet pins which served both as a means of locking the lamp in its socket and as a means of connecting one end of its filament to one side of a power source when the lamp is inserted into a socket. Then the now well-known midget flashlamp, i. e., the M-2 was introduced which has a base whose diameter is smaller than the base of the #5 and is provided with a circumferential groove in the base rather than bayonet pins. In order to adapt photoflash units for both of these types of lamps, the photoflash unit socket has been designed to normally accommodate the larger #5 lamp and then an adapter has been provided for this socket which would permit the use of the smaller M-2 lamps. This means that the photographer must remember to carry this adapter with him and insert it into the photoflash unit socket whenever he wants to use M-2 lamps.

The primary object of the present invention is to provide a dual lamp socket for a photoflash unit which permits the photographer to insert either a #5 or #25 flashlamp (large base) or an M-2 lamp (small base) into the socket without the inconvenience of removing or replacing an adapter.

The novel features that we consider characteristic of our invention are set forth with particularity in the appended claims. The invention itself, however, both as to its organization and its method of operation, together with additional objects and advantages thereof, will best be understood from the following description when read in connection with the accompanying drawings, in which:

Fig. 1 is a rear elevational view of a photoflash unit with the cover removed and incorporating a dual lamp socket constructed in accordance with a preferred embodiment of the present invention;

Fig. 2 is a side view of the photoflash unit with the socket portion shown in section and taken substantially on line 2—2 of Fig. 1;

Fig. 3 is a sectional detail of the lamp socket taken substantially on line 3—3 of Fig. 1 and showing an M-2 flashlamp in place therein;

Fig. 4 is a sectional view similar to Fig. 3 with no lamp in the socket, but showing the lamp latching means in its released position and a #5 or #25 lamp being ejected from the socket; and

Fig. 5 is a sectional view similar to Figs. 3 and 4 and showing a #5 or #25 flashlamp seated in the socket.

Broadly, this improved lamp socket comprises an automatically retractable sleeve which is normally in a forward

2

position and is held in this position by a coiled spring when an M-2 lamp is inserted into the socket. The inside diameter of this sleeve fits the outside diameter of the M-2 lamp base and acts as a socket for locating the lamp centrally of the reflector. When a #5 or #25 flashlamp (with a larger diameter base) is inserted into a socket, the lamp base forces the retractable sleeve rearwardly against the coil spring pressure until the lamp is locked in position. Both types of lamps are latched in proper position in the socket by a common releasable latching member which also connects the lamp filament to one side of a source of power in the photoflash unit. The retractable sleeve is guided in its travel by a central pilot tube which in turn guides a spring loaded central contact which is engaged and retracted by the center contact of each type of lamp as it is inserted into the socket.

Referring now to the drawings, the photoflash unit of which the socket of the present invention forms a part comprises a housing 10 of the shape best shown in Fig. 1 which is adapted to contain all of the electrical components and be molded from a plastic material for insulation purposes. The rear of the housing has a removable metal cover 11 which is held in place by a screw 12, said cover being removed to change two batteries B lying in side-by-side relation and which may constitute the power source for firing the lamps.

As is customary in the art, this photoflash unit is adapted to be detachably connected to the side wall of a camera and be electrically connected into the flash synchronizing switch controlled by the camera shutter. To this end the photoflash unit includes locating pins 13 and 14 plus an attaching screw 15 which engage corresponding holes in the wall of a camera. Each of pins 13 and 14 merely slidably engage locating holes in the camera body while attaching screw 15 engages a threaded bore in the camera body to draw the photoflash unit down tightly against the camera and force the pins 13 and 14 completely into their respective holes. Attaching screw 15 and pin 14 form parts of the electrical circuit between the flash switch in the camera and the photoflash unit components, whereas pin 13 is merely a locating pin and forms no part of the electrical circuit.

Pin 14 has a press fit with end 17 of a metal contact strap 18 which is bent up and over a pair of spaced insulating partitions 19 bearing four upstanding posts 20 for positioning the strap laterally. If the power source consists of two No. 2 batteries B adapted to be placed in the photoflash unit in side-by-side relation and with both bases downward, the end of contact strap 18 is turned down to engage and support the base of the innermost battery. The top contact of this innermost battery and the bottom contact of the outermost battery are electrically connected by an offset metal contact strap 21 which is fastened to the side wall of the photoflash unit by locating pin 13. The top contact of the outermost battery B is engaged by the turned-up end 22 of a contact strap 23 which has a turned-over ear 24 adapted to be electrically connected by a screw 25 to a metal bracket cover 26 of the form best shown in Fig. 1.

The metal bracket cover 26, which serves to connect the center contact of the lamp socket into the electrical circuit of the photoflash unit, is located in the photoflash unit by having an elongated aperture 27 in a turned-down ear 28 thereof engaging a correspondingly shaped projection on the top of partition 29 molded in the housing. This metal bracket is fastened in the housing by screws 25 and 25' threaded into the partition 29, and as mentioned above, screw 25 also engages an opening in turned-over ear 24 of contact strap 23 to connect this metal bracket into one side of the electrical circuit. The metal bracket also includes an offset apertured ear

30 which is adapted to be engaged by the threaded end of screw 12 for attaching the cover plate 11 to the photoflash unit housing. The screw 12 may be provided with a pair of radial lugs 31 which prevent the screw from falling out of the cover plate when the same is removed from the housing. The metal bracket 26 also includes an arm 32 having a turned-down projection 33 behind which one end of a thin separator 34 of insulating material is held while the other end 35 of the separator is positioned between the end 36 of an elongated metal contact 10 and lamp ejector lever 37 and the ends of partitions 19. This separator 34, along with the wall 38 of the photoflash unit housing, defines the battery compartment.

The resilient metal contact lever 37 extends substantially the full length of the photoflash unit casing and serves 15 as a part of a releasable latching means for locking the lamps in the socket as well as serving to electrically connect the lamps into the battery circuit. The lower end 36 of ejector lever 37 is forked and embraces attaching screw 15. A shoulder 38 on the attaching screw 20 is adapted to be drawn down tightly against the forked end of the lever 37 when the photoflash unit is mounted on the camera body and thus produce a good electrical contact between screw 15 and lever 37. The other end of lever 37 extends to the top of the photoflash unit 25 and terminates in an end 39 which is normally urged radially toward the lamp socket to provide a lamp latching means as will be described hereinafter.

The dual lamp socket of the present invention is in the upper, offset and rounded end of the photoflash unit housing which is molded to form a hollow casing 40 provided with a circular lamp opening 41 bounded by a circular wall 42 whose diameter is just large enough to accommodate the circular base of a #5 or #25 flashlamp and locate such lamp in a correct position relative to the reflector R. As shown in Figs. 4 and 5, a conventional #5 and #25 flashlamp has a pair of diametrically spaced bayonet pins 43 extending radially from a large diameter circular base 44 and a center contact 45. The conventional M-2 flashlamp, on the other hand, is considerably smaller than the #5 or #25 flashlamp and has a smaller diameter circular base 46, a central contact 47 and a circumferential groove 48 in its base instead of bayonet pins. While the reflector may be permanently attached to the photoflash unit, we have shown a design wherein it is detachably connected thereto for permitting the use of different size or shaped reflectors if desired. To this end, the front wall of the photoflash unit is provided with a pair of recesses 50 and 51 of different depth which are concentric to each other and the lamp socket or opening 41. Mounted on the step 52 formed by these recesses is a bayonet-type latch ring 53 behind which bayonet lugs 54 on the rear of the reflector R are adapted to be hooked by a partial rotation of the reflector to fasten the reflector to the photoflash unit.

Slidably mounted within the opening 41 and guided by the wall 42 thereof is a retractable sleeve 56 made of an insulating material. This sleeve is normally urged to a forward position by a coil spring 57, and the sleeve is limited in its outward movement by engagement of radial lugs 58 thereon which engage the end of wall 42. The inside diameter of this retractable sleeve fits the outside diameter of the M-2 lamp base and acts as a socket for locating this smaller lamp centrally in the reflector, see Fig. 3.

When a #5 or #25 flashlamp (with larger base diameter) is inserted into the socket, the lamp base engages and forces the retractable sleeve rearwardly against the coil spring pressure until the lamp is locked in position, see Fig. 5. Since the circular opening 41 defined by wall 42 corresponds to the outside diameter of the base of the #5 or #25 flashlamp, the wall 42 is provided with a pair of diametrically disposed axial slots 60 which are deep enough to pass the bayonet pins on such lamps. These slots, therefore, compel a proper orientation of

the #5 or #25 lamps for insertion into the socket so that the latch means to be described will properly engage the bayonet pins 43 to hold the #5 or #25 lamps in the socket.

5 The retractable sleeve 56 is guided in its travel by a central pilot tube 61 made of insulating material and which is in turn laterally located in the casing by turned-up lugs 62 on the metal cover bracket 26. This pilot tube is in turn held against the metal cover bracket by the action of coil spring 57. Slidably mounted within this pilot tube is a metal center contact 63 which may be provided with a sharp point 64 adapted to cut into the center base contact 45 or 47 of #5 or M-2 lamps, respectively, to provide good electrical contact, see Figs. 3 and 5. The center contact 63 is normally urged forwardly of the socket by a coil spring 65 confined between the enlarged bottom thereof and the metal cover bracket 26, and this spring 65 also serves to electrically connect the center contact to one side of the battery circuit through the metal cover bracket 26. Outward movement of center contact 63 is limited by an overhanging flange 66 on the end of the pilot tube 61, see Fig. 4.

Both types of lamps are retained in proper position in the socket and connected into the battery circuit by latch means on the end 39 of resilient contact and ejector lever 37. As clearly shown in Figs. 3-5, the end 39 of lever 37 extends axially of the socket and includes a turned-down catch portion 70 and a latching aperture 71 which is left in said end 39 by turning said catch portion 70 therefrom. The wall of the retractable sleeve 30 56 is provided with a cutout 72 which allows the catch portion 70 to extend into a position where it can engage the circumferential groove 48 of an M-2 lamp when it is pushed into the socket with a straight thrust and 35 positively latch the lamp in the socket, see Fig. 3. The latching aperture 71 is located further forward relative to the socket and is adapted to engage one of the bayonet pins 43 on the base of a #5 or #25 lamp to latch the same in the socket, see Fig. 5. The extreme edge of 40 the end 39 is flared outwardly as shown at 73 so that a bayonet pin 43 on the #5 lamp can cam the end 39 of ejector lever 37 away from the socket and slide into latched relation with the aperture 71.

Looking at Fig. 1, it will be seen that ejector lever 45 37 is fixed at its lower end 36 and is deformed at 72 so that the normal resiliency of the lever tends to move the end 39 thereof, and the catch portion 70 and the latching aperture 71 thereon, radially toward the socket and into a lamp latching position, see Figs. 3 and 5. To release 50 a lamp from a socket, end 39 of ejector lever 37 is sprung away from the socket, or to the position shown in Fig. 4, where both the catch portion 70 and the latching aperture 71 release the circumferential groove 48 of an M-2 lamp or the bayonet pin 43 of a #5 lamp, respectively. This is accomplished from the outside of 55 the photoflash unit by pressing inwardly on the end 75 of a plastic pin 76 which has a reduced end 77 engaging a hole in the ejector lever 37. A flange 78 on pin 76 engages the inside face of the photoflash unit wall to limit the outward movement of the pin and hence determine the normal position of ejector lever 37. Looking at Figs. 1 and 2, it will be seen that the ejector lever 37 is confined laterally by lying beneath the down-turned ear 28 on the metal cover bracket 26. Since each of these two 60 parts is connected into the battery circuit, to prevent short-circuiting the lamp socket a strip of insulation 80 is placed between the underside of down-turned ear 28 and the ejector lever 37.

Having thus described our invention, it is believed that it will be apparent that the disclosed dual lamp socket for flashlamps provides a fairly simple socket arrangement which can readily accommodate either M-2 or #5 and #25 type flashlamps despite the fact that each of these types of flashlamps has a different size base and 65 different means for latching the lamps in the socket.

This dual socket is so designed that either type of flash-lamp mentioned can be inserted thereinto by a straight thrust and each lamp will be positively latched in the socket in proper relation relative to the reflector surrounding the same. The latching means for each lamp not only serves to properly connect the respective lamps into the battery circuit, but is so designed that the lamp latching means for both types of lamps can be operated by a single release button on the outside of the photoflash unit. The design of this socket also is conducive to easy assembly since no soldered or wire connections are used. While we have shown our novel dual lamp socket in connection with a particular type of photoflash unit, it is pointed out that its use is not limited to such a photoflash unit but that it can be used equally well on photoflash units having different types of power sources than that disclosed and on photoflash units which are used separate from the camera and electrically connected to the flash synchronizer switch associated with the camera shutter through the use of separate wire leads rather than being mounted directly on the camera body and electrically connected to the synchronizer switch by means of such mounting.

Although we have shown and described certain specific embodiments of our invention, we are fully aware that certain modifications thereof are possible. Our invention, therefore, is not to be limited to the precise details of construction shown and described but is intended to cover all modifications coming within the scope of the appended claims.

Having thus described our invention, what we claim as new and desire to secure by Letters Patent of the United States is:

1. A dual lamp socket for a photoflash unit adapted to releasably seat interchangeably regular flashlamps having a base from which bayonet pins extend radially and midget flashlamps having a base of smaller diameter than said regular lamps and having a radial flange extending circumferentially thereof and connect them in circuit with a power source carried by the photoflash unit and comprising in combination a hollow casing provided with a circular opening into which the lamp bases are adapted to be inserted and having an internal diameter slightly larger than the exterior diameter of the base of a regular lamp, diametrically disposed radial slots in the wall forming said opening adapted to pass the bayonet

- pins extending radially from the base of the regular lamp, a pilot sleeve made of insulating material fixed in the bottom of said casing and in axial alignment with said opening therein, a metal center contact slidably mounted within said pilot sleeve and adapted to engage the center contact of any lamp inserted into the socket, a coiled spring normally urging said center contact to an extended position and serving to electrically connect said contact to one side of the power source, cooperating means on said center contact and said pilot sleeve limiting the outward movement of said contact, a retractable sleeve slidably mounted on the exterior of said pilot sleeve and having an internal diameter slightly larger than the outside diameter of the base of a midget lamp, whereby it is adapted to act as a socket therefor, and having an external diameter substantially equal to the diameter of the base of a regular lamp, a coiled spring normally urging said retractable sleeve to an extended position, cooperating lugs on said retractable sleeve and said casing limiting the outward movement of said sleeve to said extended position, and a single releasable metal latch member within said casing adapted to positively engage a bayonet pin on the base of a regular lamp and the radial flange on the base of a midget flashlamp when one or the other type of lamps is pushed into said socket with a straight thrust to latch the lamp in said socket and at the same time connect the lamp base to the other side of said power source in the photoflash unit.
2. A dual lamp socket for a photoflash unit according to claim 1 in which the wall of said retractable sleeve is provided with an axial slot aligned with one of the radial slots in the wall of said opening, and in which said releasable latch member includes a projection normally extending radially into said axial slot in said sleeve to positively engage said radial flange on the base of a midget lamp when the same is inserted into said socket and includes a catch member normally extending axially of the exterior of said sleeve to positively engage one of the bayonet pins on the base of a regular lamp when it is inserted into said socket, and means extending to the outside of said casing to move said release member radially from its normal position relative to said retractable sleeve to move said projection and catch from their latching positions.
